UNITED STATES PATENT OFFICE.

GEORGE MARION MORRIS, OF COHOES, ASSIGNOR OF ONE-HALF TO WILLIAM I. BLEAKLEY, OF LANSINGBURG, NEW YORK.

LIFTING AND ROTATING PRESSER-FOOT DEVICE.

SPECIFICATION forming part of Letters Patent No. 289,687, dated December 4, 1883.

Application filed May 2, 1883. (No model.)

To all whom it may concern:

Be it known that I, GEORGE MARION MORRIS, of the city of Cohoes, county of Albany, and State of New York, have invented a new and useful Improvement in Lifting and Rotating Presser-Foot Devices for Sewing-Machines, of which the following is a specification.

My invention relates to a mechanism whereby the presser-foot of a sewing-machine may be rotated after having been raised from off the table-plate, so as to swing around away from the needle horizontally on the guide-bearings of the upwardly-extended shank, the object of my invention being to produce a promptly-acting means for moving the foot around after having been raised from off the fabric being sewed, for the more convenient adjustment of the latter, and to produce a prompt means for returning the foot to its position on the fabric after the adjustment of the latter has been made.

My invention is more particularly adapted to that kind of foot-raising mechanism in which the foot and attached vertical shank, on which a spiral spring is placed, are raised by a lifting-cam constructed to have a horizontal offset journal-bearing on the needle-arm standard, and operated by a spoke-handle, and the engagement of said rotated cam with the undersurface of an offset cap constructed upon and secured to the top of the foot-shank, the latter moving in vertical guide-slides formed in brackets on the standards, and against the recoil force of a spiral spring which surrounds it.

Accompanying this specification, and forming a part of it, is a sheet of drawings containing two figures illustrating my invention and the parts of a sewing-machine with which it connects, the same designation of parts by letter-reference being used in both. Figure 1 shows in perspective the foot-lifting mechanism of a sewing-machine with my invention attached thereto, and the foot being illustrated as down upon the table-plate. Fig. 2 shows in perspective the same parts as are shown at Fig. 1, with the foot as raised and swung around.

The parts of the mechanism shown in the foregoing illustrations are designated by let-

ter-reference and their function explained as follows:

The letter A indicates that part of a sewing-machine arm which connects with the foot-raising mechanism, so as to sustain the pendant needle-bar N and the foot-shank R, as well as the connected foot F.

The letters B' and B² designate two brackets attached to the arm A at its end, in which brackets are constructed vertical guideways 55 O' and O" for the shank R to move in.

The letter S indicates a spiral spring surrounding the shank, and e a stop for the said spring.

D' designates a vertical slot made in the upper bracket, B', and D² a guide-bar on the shank R, constructed to move in said slot.

The letter C indicates a lifting-cam, having a horizontal offset shaft to journal in a shaft projected from the side of the stud J, the latter 70 being extended upwardly from the bracket B', on which shaft said lifting-cam is adapted to be rotated by the handle H.

The letter I designates a cap attached to the top of the shank R, the under edge of which cap projects horizontally over, so as to engage with the lifting-cam C (indicated at e²) when the cam is turned to raise the cap, connected shank, and foot against the recoil force of the spring S.

All of the parts thus described constitute the ordinary and well-known parts of a sewing-machine, and they are only illustrated and their operation explained to better show the operation of the parts constituting my improvement and invention and their connection therewith.

To actuate the shank R and connected foot to be turned around after having been raised by the mechanism before described, so that the foot shall not be beneath the needle, there is constructed on the outer edge of the lifting-cam C, and where nearest to the shank the peripheral groove a', and connected with the latter, at right angles to it, the transverse groove i, the said groove i being made parallel to the shaft on which the lifting-cam turns, and terminating in the face of the latter, as indicated at i'.

The letter n designates a pin downwardly 100

projected from the under surface of the overhanging edge of the cap I, and this pin is adapted to run in said peripheral groove a' when the lifting-cam C is in engaging contact 5 with the under surface of the overhanging cap I, and the latter attached shank and foot are being raised thereby. So soon as the parts are thus raised sufficiently to take the guide-bar D² from out of the slot D', the pin n turns 10 from the peripheral groove a' into the transverse groove i, and the cap, attached shank, and foot commence to turn and swing around the shank pivoted in the vertical bearings O' and O² in the brackets, the bottom of the guide-bar D² moving around on the top surface of 15 the bracket B', as indicated at Fig. 2. To turn the raised cap, attached shank, and foot still farther around by means of the lifting-cam C and handle H, notches v v are formed 20 in the rim of the cap I, and pins m m projected from the perimeter of the lifting-cam C, which pins engage with said notches so as to gear into them, and thus continue the turning of 25 the cap, attached shank, and foot until the limit of revolution is reached, when the parts are held in place, as thus raised and turned, by the engagement of the bottom of the guide D² on the top of the bracket B', and with the 30 parts as shown at Fig. 2.

3c To restore the mechanism to a position with the foot upon the table, as appearing at Fig. 1, the foot is moved around by the finger or thumb until the guide D² comes over the slot D', when the recoil force of the spring promptly 35 forces the foot to its place upon the material being sewed beneath the needle.

Where it is desired in operating the sewing-machine to take off and put on a hemmer or binder, or where the material to be sewed must

be turned and changed in position, as is particularly the case with knit fabrics, my invention adds much to the facility and the rapidity with which work of this kind can be done.

Having thus described my invention, what 45 I claim, and desire to secure by Letters Patent, is—

1. In an attachment to a sewing-machine for raising the foot, the lifting-cam C, formed with the peripheral groove a' , terminating in 50 a transverse groove, i, in combination with the cap I, provided with the pin n, adapted to engage with said grooves, substantially as and for the purpose set forth.

2. The lifting-cam C, formed with the peripheral groove a' , terminating in the transverse groove i, and provided with pins m m, in combination with the cap I, provided with the pin n and notches v v, adapted to engage, respectively, with the grooves named and pins 60 on the cam, substantially as and for the purpose stated.

3. The lifting-cam C, formed or provided with the peripheral groove a' , terminating in a transverse groove, i, and provided with pins 65 m m, and a cap, I, having a pin, n, and notches v v, in combination with the foot-shank R, formed with the guide D², adapted to slide in a groove, D', formed in the upper bracket of the head-piece, and to hold the parts in elevation, substantially as described.

Signed at the city of Troy, this 19th day of April, 1883, in the presence of two witnesses.

GEORGE MARION MORRIS.
